UNITED STATES PATENT OFFICE

FRANCIS S. MADDAFORD, OF BALTIMORE, MARYLAND, ASSIGNOR TO CROSSE & BLACKWELL, INCORPORATED, OF BALTIMORE, MARYLAND, A CORPORATION OF MARYLAND

DESIGN FOR A JAR

Application filed May 6, 1931. Serial No. 39,740. Term of patent 14 years.

To all whom it may concern:

Be it known that I, FRANCIS S. MADDAFORD, a citizen of Great Britain, residing at Baltimore, in the county of Baltimore and State of Maryland, have invented a new, original, and ornamental Design for Jars, of which the following is a specification, reference being had to the accompanying drawings, forming a part thereof.

In the drawings:

Fig. 1 is a side elevational view of a jar embodying my design.

Fig. 2 is a sectional view taken along the line II—II of Fig. 1.

I claim:

The ornamental design for a jar substantially as shown.

Signed at Baltimore, in the county of Baltimore and State of Maryland, this 1st day of May, 1931.

FRANCIS S. MADDAFORD.
